UNITED STATES PATENT OFFICE

JOSEPH ROBINSON, OF NEW YORK, N. Y.

AUTOMATIC TRAIN-PIPE COUPLING

Application filed April 26, 1926, Serial No. 104,765. Renewed January 15, 1929.

My invention relates to automatic train pipe couplings, and more particularly to brackets, or universal supports, for such couplings. Among its objects are to provide an improved means for permitting universal movement to the coupling head, the means including especially an improved bracket which is inexpensive to make, simple, strong, and very efficient.

10 The invention resides in the combinations, arrangements and improvements hereinafter described, pointed out in the appended claims, and illustrated in the accompanying drawings in which—

15 Figure 1 is a sectional side elevation of my improvement.

Figure 2 is a front elevation of the bracket A shown in Figure 1. In this view the member C is shown in section, and the tie rod 7 is omitted.

20 Figure 3 is a horizontal sectional view through the center of the anchor device or lower end D of the bracket. In this view the forward end of the tie rod 7 is shown 25 in elevation.

Figure 4 is a section through the bracket on substantially the line 4—4 of Figure 2.

Referring now to the drawings: I attach my improved bracket A to a suitable lug B 30 of a car coupler, not shown. A member C, such as shown in my co-pending application, Serial No. 364,920, filed March 11th, 1920, for improvements in automatic train pipe connectors, spans the lower end D of the bracket, and carries at its forward end a suitable coupling head—not shown. The member is provided with a vertically extending projection 5 against which a buffer or supporting spring 6 is seated. The spring yieldingly supports the member C and the coupling head (not shown) with the flange 5 normally bearing firmly against the rear side of the bracket. The spring surrounds a one-piece tie rod 7, which extends through the flange 5 and is hooked over the anchor device or lower end D of the bracket and carries at its rear end an adjustable abutment 8 by which the spring 6 is held in place, and is tied to the tie rod 7, under compression. These parts, 45 with the exception of the bracket A, are in

substantially the same relative arrangement, and of substantially the same construction and function as the similar parts in my aforesaid co-pending application.

With few exceptions the designs of previous brackets are such that they must be made by the expensive method of casting. The relatively few types which might be forged are of cumbersome design, and hence 55 very costly to manufacture.

60 One of the objects of my invention is to eliminate these objections and greatly reduce the cost of manufacturing an automatic train pipe coupling bracket. I accomplish this object by simplifying the bracket and so designing it that it may be readily forged or 65 pressed from suitable material. My improved bracket A is formed of three pieces, 9, 10 and 11, part 9 and 10 being complementary halves, and the part 11 being a T shaped 70 cross bar which forms a seat against which the flange 5 rests. The halves 9 and 10 are preferably pressed from a suitable flat wrought iron or steel bar, the upper end of 75 each part being flared or off-set laterally to span the lug B, and each part having vertically spaced punched or drilled holes to receive the bolts 12, by which the bracket is clamped to the lug B. At 14 each half of the 80 bracket A is spread or opened to admit the tongue 15 of the cross bar 11. To secure the cross bar in position, and also to position the halves 9 and 10 in proper relation one to the other, a rivet or other suitable means 16 is passed through the halves 9 and 10, and the 85 tongue 15, at this point.

85 The lower end, or anchor device D, of each half of the bracket A is semi-circular in cross section at 17, (Figure 2) so that when the halves are secured together by the rivet 16 and 90 the bolts 12, a seat 18, cylindrical in cross section, is formed, and into the seat is mounted, for rocking movement thereon, the forward end of the tie rod 7—see especially Figures 1 and 3. The forward end of the tie rod is provided with an elongated opening 19, and 95 which allows the tie rod to be assembled into the seat 18 by passing it upwardly over the lower end or anchor device D of the bracket. To prevent dislodgment of the tie rod 7 from 100

its seat 18 on the bracket the lower wall of the seat is extended forwardly slightly as shown at 20 in Figure 1. Any possibility of the lower end of the halves 9 and 10, which form the anchor device D, spreading in service is provided against not only by the rivet 16 but also by the forward end of the tie rod 7, which spans these parts and constitutes, in cooperation with the spring 6, locking or clamping means for preventing such spreading—see especially Figure 3. The tie rod at the point where it engages the seat 18 is round in cross section, as shown in Figure 1, and it and the seat 18 therefore flare in opposite directions at their point of contact.

To form a seat on the bracket A for the member or pipe C, and to prevent dislodgment of the member from the bracket in event any of the parts break in service, the extreme lower ends of the halves 9 and 10 are turned outwardly, as at 21. Upon these out-turned portions the sides, or straps 22, of the member C slidingly rest. The straps are provided with inclined or curved shoulders 23 and 24 which contact with the out-turned portions 21 and the cross bar 11 to position the member C and the coupling head when the automatic coupling moves to the normal uncoupled position. This arrangement prevents undue rotation of the coupling head when in the uncoupled position, and permits of limited rotation thereof when in the coupled position, thus increasing the flexibility of my improved universal joint.

The opening 19 in the tie rod 7 is of course large enough to permit the tie rod to be passed upwardly over the portions 21 into its seat 18 on the anchor device D.

What I claim is:

1. An automatic train pipe coupling comprising in combination, a coupling head, a hollow member secured thereto and provided at its rear end with a perforated projection, a tie rod extending through the perforation in said projection into said hollow member, an abutment on said tie rod, a spring confined between said abutment and said projection for yieldingly sustaining said coupling head, a cross bar against which said projection normally bears, and a bracket extending from above downwardly through said hollow member and said tie rod, said bracket being formed of separate halves suitably secured together, the lower end of which halves form a seat on which said tie rod is mounted for rocking movement, the halves of said bracket being off-set intermediate their ends to receive said cross bar.

2. In an automatic train pipe coupling, the combination of a coupling head, a hollow member secured thereto, means for yieldingly sustaining said member and said coupling head, said means including a tie rod, a bracket extending from above said member downwardly there-through and through said

tie rod, said bracket being formed of separate halves suitably secured together and having at its lower end integrally formed out-turned portions, a cross bar secured between the halves of said bracket at a point above said tie rod, and means on said member for cooperating with said cross bar and said out-turned portions to properly position said member on said bracket when in the normal uncoupled position.

3. A bracket for an automatic train pipe coupling, comprising separate halves each of which is off-set at its upper end to span a lug, and each of which is provided at its lower end with a semi-circular seat for a tie rod, out-turned portions at the lower end of each half of the bracket, a cross bar secured between the halves of the bracket at a point above said tie rod seat, and means for securing the halves of said bracket together.

4. A bracket for an automatic train pipe coupling, comprising separate halves each of which is off-set at its upper end to span a lug, and each of which is provided at its lower end with a semi-circular seat for a tie rod, out-turned portions at the lower end of each half of the bracket, a cross bar secured between the halves of the bracket at a point above said tie rod seat, and means for preventing spreading of the halves of said bracket at the point where they form said seat, said means including a tie rod extending around the lower end of said bracket and mounted on said seat.

5. A bracket for automatic train pipe connectors, comprising two flat complementary halves rigidly secured together, a cross bar secured between said halves intermediate their lengths, each of said halves below said cross bar being made substantially semi-circular in cross section, whereby a substantially circular anchor device is formed adjacent the lower end of said bracket.

6. A bracket for automatic train pipe connectors, comprising two flat complementary halves rigidly secured together, said halves at their upper portion being separated to permit receiving a lug therebetween, each of said halves adjacent its lower end being provided with a semi-circular portion, whereby a substantially circular seat is formed on the bracket, and each of said halves at its lower end being provided with an out-turned end.

7. A bracket for automatic train pipe connectors, comprising two complementary portions rigidly secured together, a cross bar secured between said portions intermediate their lengths, each of said portions below said cross bar being rounded on its front edge, whereby a curved seat is formed on the front edge of the bracket.

8. A bracket for automatic train pipe connectors, comprising two complementary portions each provided with a flat face, means for securing said portions together with

their flat faces in contact, a cross bar secured between said portions intermediate their lengths, each of said portions at its lower end being bent laterally away from the other portion, each of said portions above its lower end being rounded on its front edge, whereby a curved seat is formed on the front edge of the bracket above said laterally bent portions.

10 In testimony whereof I hereunto affix my signature.

JOSEPH ROBINSON.
